UNITED STATES PATENT OFFICE.

CHARLES SCHUETZ, OF NEWARK, NEW JERSEY.

CLIP FOR DROP-LIGHT WIRES.

SPECIFICATION forming part of Letters Patent No. 601,860, dated April 5, 1898.

Application filed December 1, 1896. Serial No. 614,046. (No model.)

To all whom it may concern:

Be it known that I, CHARLES SCHUETZ, a citizen of the United States of America, and a resident of Newark, in the county of Essex and State of New Jersey, have invented certain new and useful Improvements in Clips for Drop-Light Wires, of which the following is a specification.

My invention has reference to improvements in means for adjusting the height of electric drop-lights, and has for its objects, first, to provide a clip which can be placed in position on the wires subsequently to the suspension of the lamp without detaching the wires, and, secondly, to insure at the same time a positive suspension of the lamp at any desired elevation.

Many devices have been constructed for the purpose of effecting the adjustment of electric drop-lights—such, for instance, that commonly termed a “peanut” and that made in the form of a ball provided with two parallel perforations. The former, while being applicable after the suspension of the lamp, is difficult to apply and has unguarded lateral openings, while the latter form cannot be applied without detaching the wires from the lamp and does not grip the wires sufficiently hard to prevent a slight pull from lowering the lamp. To overcome these objectionable features, I provide a clip formed of three portions linked together, to wit—a central link or body and two outer open links hinged at separate points to said central link and by removable pins—said parts being so constructed and disposed that the weight of the lamp will cause the device to grip the wires and that any pull on said lamp or wires increases the hold of the clip on said wires.

The nature of my invention will best be understood when described in connection with the accompanying drawings, in which—

Figure 1 represents a side elevation of the clip, the wires being indicated by broken lines. Fig. 2 is a perspective view of the clip. Fig. 3 is a front elevation thereof. Fig. 4 is an elevation on a smaller scale, showing the clip attached to the drop-wires of an electric lamp.

Similar letters of reference designate corresponding parts throughout the several views of the drawings.

Referring to the drawings, the letters A and

B designate two outer open links, preferably made **U**-shaped and entirely or partly of any suitable non-conducting material, such as a 55 hard or tough wood or rubber.

C is the central link, made likewise of non-conducting material, and to which the outer links A and B are pivoted by removable pins a and b, which may be in the form of split 60 pins, as shown in the drawings.

The central link C is provided with inclined or cam-shaped terminals c and c', which project beyond the connecting-pins a b and into the **U**-shaped openings of the outer links. 65 Said terminals quite closely approach the closed ends of said outer links, or, if desired, they may be caused to pass the same.

To apply the clip to the wires, the connecting-pins a b are withdrawn and the two outer links slipped over the wires and again connected to the central link by said pins, the relative position of the parts and the wires being then as shown in Figs. 1 and 4. The weight of the lamp now tends to straighten 75 out the clip, and consequently the outer links and the central link coöperate in wedging the wire between them. An inadvertent pull on the wires will only cause the grip to more firmly wedge the former. By subsequently 80 turning the outer links by hand the wires can be drawn through the clip to adjust the position of the lamp.

It will be readily understood that with the present construction I am enabled to attach 85 the clip without detaching the wires from the lamp, while at the same time the device is free from unguarded openings, and consequently the wires cannot become disengaged from the clip. 90

What I claim as new is—

1. A clip for adjusting the height of electric lamps, consisting of two recessed substantially **U**-shaped links adapted for the passage of the wires, a central link having cam-shaped 95 ends projecting into the recesses of said outer links, and removable pins passing through the outer links and central link and hinging the former to the latter at different points, so as to permit said outer links to swing in line 100 with the longitudinal axis of the central link, substantially as described.

2. A clip for adjusting the height of electric lamps, consisting of two recessed, substan-

tially U-shaped links adapted for the passage of the wires, a central link having its ends projecting into the recesses of said outer links, and removable pins passing through the outer links and central link and hinging the former to the latter at different points, so as to permit said outer links to swing in line with the longitudinal axis of the central link, substantially as described.

In testimony that I claim the foregoing as my invention I have signed my name, in presence of two witnesses, this 27th day of November, 1896.

CHARLES SCHUETZ.
